UNITED STATES PATENT OFFICE.

ROLLIE B. FAGEOL, OF OAKLAND, CALIFORNIA.

DESIGN FOR A MOTOR-VEHICLE WHEEL AND FENDER ASSEMBLY.

59,728.

Specification for Design.

Patented Nov. 22, 1921.

Application filed May 26, 1921. Serial No. 472,901. Term of patent 14 years.

To all whom it may concern:

Be it known that I, ROLLIE B. FAGEOL, a citizen of the United States, and a resident of Oakland, county of Alameda, State of California, have invented a new, original, and ornamental Design for a Motor-Vehicle Wheel and Fender Assembly, of which the following is a specification, reference being had to the accompanying drawings, forming part thereof.

The drawing is a side elevation of a motor vehicle wheel and fender assembly illustrating my new design.

I claim:

The ornamental design for a motor vehicle wheel and fender assembly substantially as shown and described.

ROLLIE B. FAGEOL.
